ABRAHAM RODRIGUEZ AND HENRY GUSTAVSON, OF SAN JOSE, CALIFORNIA, AS-SIGNORS TO MILTON G. MOENNING AND DOUGLAS C. HOWARD, BOTH OF SAN JOSE, CALIFORNIA.

PUMP ASSEMBLY.

Application filed October 8, 1921. Serial No. 506,498.

To all whom it may concern:

Be it known that we, ABRAHAM RODRIGUEZ and HENRY GUSTAVSON, citizens of the United States, and residents, respectively, of

- 5 San Jose, in the county of Santa Clara and State of California, have invented certain new and useful Improvements in Pump Assemblies, of which the following is a specification.
- 10 It is the object of our invention to provide a construction wherein the several bowls of a string forming a part of a deep well centrifugal pump may be quickly and easily separated at any desired point and as
- 15 quickly and easily reassembled.

The drawing is a vertical transverse section through a portion of a deep well centrifugal pump embodying our invention.

- Referring more particularly to the drawing, 1 indicates a pump bowl having a bearing 2 formed integrally therewith and supported by diffusion vanes 3. Bowl 1 is provided with an upper and externally threaded neck 4 and a bottom and interiorly threaded socket 5. These threaded necks and sockets are of the same diameter so that any required number of bowls may be arranged in the stack, and any bowl may be removed if desired and another inserted in 30 its place.

In bowl 1 is formed an impeller chamber 6, an impeller 7 being shown therein. At 8 is shown a shaft section engaging bearing 2 and extending a distance above the upper 35 edge of bowl 1 and tapped as at 9. The lower end of shaft section 8 is threaded as at 10 to engage the threaded impeller, the

threaded portion passing clear through the impeller and extending a distance below the same to engage the tapped portion 9 of the 40 next lower shaft section.

By means of this construction any bowl in the stack may be quickly and easily detached from adjacent bowls, the shaft section therein detached from the adjoining 45 shaft sections and the whole removed and replaced with another bowl if so desired, or the stack lengthened by the addition of other bowls and shaft sections, or shortened by assembling without the replacing of the 50 removed parts.

This construction also provides a compact and rigid stack easily insertable in and withdrawn from a well bore of slightly larger 55 diameter than the bowls themselves.

It is to be understood, of course, that while we have herein shown and described one particular embodiment of our invention, changes in form, construction and method of operation may be made within the scope of 60 the appended claims.

We claim:—

In a centrifugal pump, a shaft section internally threaded at one end to receive the threaded end of another shaft section and externally threaded at the other end to engage the internally threaded end of another shaft section, and an impeller internally threaded to engage said last mentioned externally threaded end of said shaft section, 70 and mounted thereon prior to its engagement with another shaft section.

ABRAHAM RODRIGUEZ.
HENRY GUSTAVSON.
